Patented July 10, 1962

193,214

BINOCULAR MICROSCOPE OR SIMILAR ARTICLE

Harry Preble, Jr., Cross River, N.Y., assignor to The
A. C. Gilbert Company, New Haven, Conn., a corpo-
tion of Maryland

Filed June 14, 1961, Ser. No. 65,589

Term of patent 14 years

(Cl. D57—1)

Fig. 1

Fig. 2

Fig. 3

Fig. 4

Fig. 5

FIG. 1 is a perspective view of a binocular microscope, showing my new design;

FIG. 2 is a top plan view thereof;

FIG. 3 is a front elevational view thereof;

FIG. 4 is a side elevational view thereof;

FIG. 5 is a rear view thereof.

The side not shown is substantially the same as the side shown.

I claim:

The ornamental design for a binocular microscope or similar article, substantially as shown.
